(57) **CLAIM**

The ornamental design for an adapter for an aerodynamic housing for a left external wheel of a vehicle, as shown and described.

DESCRIPTION

FIG. 1 is a front, top, left side perspective view of an adapter for an aerodynamic housing for a left external wheel of a vehicle in accordance with the present invention;

FIG. 2 is a back, bottom right perspective view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a left view thereof; and,

FIG. 9 is a front, top, left side perspective, environmental view thereof.

The dashed and broken lines are for the purpose of illustrating design features and form no part of the claimed design.
